US00D982580S

(12) **United States Design Patent** (10) **Patent No.:** **US D982,580 S**
(45) **Date of Patent:** **** Apr. 4, 2023**

(54) **WATCH WITH DISPLAY**

(71) Applicant: **Garmin Switzerland GmbH**,
Schaffhausen (CH)
(72) Inventors: **Graham F. Robillard**, Overland Park,
KS (US); **Dustin L. Kelsey**, Bonner
Springs, KS (US); **Todd P. Register**,
Olathe, KS (US)

(73) Assignee: **Garmin Switzerland GmbH**

(**) Term: **15 Years**

(21) Appl. No.: **29/767,489**

(22) Filed: **Jan. 22, 2021**

(51) **LOC (14) Cl.** **14-02**

(52) **U.S. Cl.**

(57) **CLAIM**

The ornamental design for a watch with display, as shown and described.

DESCRIPTION

FIG. 1 is a front perspective view of a watch with display according to the present invention;

FIG. 2 is a rear perspective view of the watch with display;

FIG. 3 is a front view of the watch with display;

FIG. 4 is a rear view of the watch with display;

FIG. 5 is a left side view of the watch with display;

FIG. 6 is a right side view of the watch with display;

FIG. 7 is a top view of the watch with display; and,

FIG. 8 is a bottom view of the watch with display.

The broken lines shown in the drawings represent portions of the watch with display that form no part of the claimed design.

1 Claim, 5 Drawing Sheets
